US0D1077950S

(12) **United States Design Patent** (10) **Patent No.:** **US D1,077,950 S**
(45) **Date of Patent:** **** Jun. 3, 2025**

(54) **WEIGHT PLATE FOR ATHLETICS**

(71) Applicant: **Omnigem Ltd**, Walsall (GB)

(72) Inventors: **Abdul Wajed Choudhury**, Walsall (GB); **Charlie Meadows**, Walsall (GB); **Alex Lee**, Walsall (GB)

(73) Assignee: **Omnigem LTD**, Walsall (GB)

(**) Term: **15 Years**

(21) Appl. No.: **35/517,799**

(22) Filed: **Mar. 30, 2023**

(80) **Hague Agreement Data**

Int. Filing Date: **Mar. 30, 2023**

Int. Reg. No.: **DM/230073**

Int. Reg. Date: **Mar. 30, 2023**

Int. Reg. Pub. Date: **Jul. 14, 2023**
